TEXTILE BEAMER OR WARPER

Homer W. Groce and Godfrey H. Browne, Gastonia, N. C., assignors to Cocker Machine & Foundry Company, Gastonia, N. C., a corporation of North Carolina

Application January 26, 1951, Serial No. 208,038

12 Claims. (Cl. 28—38)

1

This invention relates to machines ordinarily known as beamers or warpers, used in the textile industry to wind warp yarns onto beams which are afterwards mounted in looms for weaving of the yarns into cloth of various kinds.

In such apparatus, the beams are constantly rotated by power, while a press roll is yieldingly held in rolling contact with the yarn accumulations on the beams during the winding or beaming period. With beamers or warpers, as heretofore constructed, considerable difficulty has been experienced in maintaining the press rolls in full longitudinal contact with the yarn accumulations on the beams, and also in accurately controlling the speed of the latter. Due to uneven tensioning of the warps and variation in the density of the windings on the beams under these conditions, irregularities frequently occurred in the fabrics subsequently woven from the yarns.

The main object of our invention is to overcome the above disadvantages. This desiderata is realized in practice, as hereinafter more fully disclosed, through provision in apparatus of the character referred to, of simple and reliable means whereby the press roll is held in constant yielding pressure engagement with the beam, and means whereby said roll is positively maintained at all times in true parallelism with the beam, in association with means whereby the speed of the beam is automatically controlled to compensate for gradual increase in the diameter of the yarn windings so that both the linear speed of the warps and the tension thereof will be kept constant throughout the beaming periods.

A further aim of our invention is to provide, in connection with a textile beamer or warper having the foregoing attributes, likewise simple and reliable beaming, loading and doffing means capable of actuation from the aforementioned means by which the press roll is held in yielding pressure contact with the beam during the beaming.

Other objects and attendant advantages will appear from the following detailed description of the attached drawings, wherein Fig. 1 is a view, in side elevation, of a textile beamer or warper conveniently embodying our invention.

Fig. 2 is a broken out view partly showing the apparatus in top plan, and partly in horizontal section.

Fig. 3 shows the apparatus in longitudinal section, with the beam in position ready for the winding to begin.

2

Fig. 4 is a view like Fig. 3 but showing an empty beam positioned in readiness to be mounted in the apparatus.

Fig. 5 is a fragmentary view in elevation looking as indicated by the angled arrows V—V in Fig. 2.

Fig. 6 is a view looking as indicated by the angled arrows VI—VI in Fig. 5.

Figs. 7 and 8 are illustrations corresponding respectively to Figs. 5 and 6 with portions broken away and in section, and with certain of the movable parts shown differently positioned.

As herein illustrated our improved textile beamer or warper has a base 1 and two main side frames 2 with upstanding lugs 3 in which a pair of longitudinally-extending parallel guide rails 4 are secured, said rails being in the form of cylindric rods. Slidable along the guide rails 4 are carriages 5 with brackets 6 wherein the opposite ends of a shaft 7 about which the press roll indicated at 8, freely revolves. The bearings 6 are united by a transverse bar 9 which is connected, at its mid-point, to the piston rod 10 of a horizontally-arranged double-acting cylinder 11 which is secured centrally of a tie beam 12 extending crosswise between the rear ends of the guide rods 4. Affixed to and extending rearwardly from the carriages 5 are toothed racks 17 that mesh with spur pinions 18 fast on a transverse shaft 19 whereof the opposite ends are rotatively supported in bearing brackets 20 clamped to the guide rods 4. By the means just described, the carriages 5 are constrained to move in unison to insure maintenance of the press roll 8 in accurate parallelism with the beam indicated at 21 onto which the warps are wound during the operation of the apparatus. For the purpose of stabilizing of the press roll 8 as it is urged forward by the piston rod of the cylinder 11 and held in yielding pressure engagement with the warps as the latter build up on the beam 21, we have devised a snubbing means which comprises a pair of arms 22 which are pivotally connected to the carriages 5. Like the racks 17, the arms 22 extend rearwardly from the carriages to respectively engage between pairs of friction plates 23 which are rockably supported on studs 24 projecting laterally from the brackets 20. In each instance a spring 25, reguatable by a hand wheel 26 in threaded engagement with the stud 24, urges the outer plate toward the inner plate of each pair 23 to create the friction.

As shown in Fig. 2, the beam 21 is mounted between drive heads 27 at the inner ends of

two spindles 28 rotative in pairs of spaced bearings 29 on supplemental standards 30 rising from the base 1 at the front of the beamer outwardly of the frames 2. The heads 27 are identical in construction, each having, see Figs. 1, 3 and 4, an arcuate slot 31 which extends from the periphery of the head to the center for reception of the corresponding journal 32 of the beam 21. Recessed into a diametral groove 33 in the inner face of each head 27 respectively on opposite sides of the head center and held in assembly by removable cover plates 34, are opposing jaw elements 35 and 36 with V notches between which the corresponding beam journal 32 is adapted to be clamped as shown in Fig. 6. The jaw piece 35 is shiftable in the groove 33 by means of a regulating screw 37 with a polygonal end accessible for wrench application at the periphery of the head 27. The screw 37 is prevented from shifting axially as it is turned through cooperation of spaced collars 38 thereon with stop shoulders on a block 39 set into a separable segmental portion 40 of the head. As shown in Figs. 5, 6, 7, the block 39 is secured to the segment 40 by screws 41, and the segment to the body of the head 27 by screws 42. The jaw piece 36 is separately adjustable in the groove 33 by means of a set screw 43 threadedly engaged in a plug 44 which closes the corresponding end of said groove. By the latter adjustment, the head 27 is adaptable for the reception of beam journals 32 of different diameters. Endwise shiftable in a transverse opening 45 in each head 27 at a radial distance from the spindle axis, is a pin 46 of square section whereof the inner end is rounded as at 47 to engage into an aperture in the corresponding end flange 48 of the beam 21 as shown in Figs. 2 and 5. From Fig. 7, it will be noted that the jaw piece 35 is formed at one side, adjacent its outer end, with a bevel edge 49, and the pin 46 with a lateral stud projection 50. Accordingly, as the jaw piece 35 is moved outward of the slot 33, the pin 46 is concurrently withdrawn, against the resistance of a spring indicated at 51, from the aperture in the beam flange 48 through camming action of the bevel edge 49 with the stud 50 as shown in Fig. 7.

Referring now to Figs. 1 and 2, the shafts or spindles 28 to which the heads 27 are affixed, are driven, through the medium of sprocket chains 55, from a transverse transmission shaft 56 journaled in bearing brackets 57 on the base 1, and powered through a belt drive 58 from an electric motor 59.

For the mounting and removal of the beam 21, we have devised a doffing means which is arranged to be actuated through connections with the cylinder 11. As shown, this means comprises a pair of arms 60 which are secured to a transverse rock shaft 61 rotatively supported in bearings 62 at the front end of the base 1 somewhat rearward of the vertical plane containing the beam drive axis. At its distal end, each arm 60 has forwardly open lateral notch 63 for engaging over the corresponding journal 32 of the beam immediately outward of the adjacent end flange 48 of the latter. For temporary retention of the beam journal 32 within the notches 63 we have provided U-shaped keeper elements 65 which are slidable longitudinally of the distal ends of the arms 60 and which have upwardly-projecting manipulating grasps 66. Normally, during operation of the apparatus, the doffing arms 60 occupy the upright positions (see Fig. 3) leaning against the front ends of the

side frames 2, being locked in this position by a latch 67 on one of said arms, which latch hooks over a catch 68 on the base 1 and which is releasable by means of the treadle indicated at 69. As instanced in Fig. 4, each doffing arm 60 is connected to the corresponding press roll carriage 5 by a chain 70 threaded through a slot in the frontal top corner of the corresponding side frame 2, said chain passing over a sprocket wheel 71 free on a shaft 72 journaled in said frame adjacent the front end thereof.

For automatically controlling the rotary speed of the press roll 8 to compensate for the constantly increasing diameter of the warp winding on the beam for maintenance of uniform tension on the warps throughout the beaming period, we have shown mechanism which except for certain details, is generally similar to that disclosed in U. S. Patent 2,384,879 granted to J. C. Bodansky and Ernest K. Whitener on September 18, 1945. Briefly described, this mechanism is as follows:

Affixed to the shaft 7 of the press roll 8 within one end of the latter, see Fig. 2, is a spur pinion 75 that meshes with a spur gear 76 at the inner end of a countershaft 77 rotatively supported in the carriage 5 at the corresponding side of the apparatus. An endless sprocket chain 78 is engaged over a sprocket pinion 79 at the outer end of countershaft 77, see Figs. 1, 2, 3, 4, said chain being directed downward to a pair of idlers 80 and 81 which are rotatively free on studs 82 and 83 projecting laterally from the carriage 5. In underpassing the idlers 80 and 81 the chain 78 is directed horizontally to sprocket wheels 85 and 86 whereof the former is secured to the shaft 72, and the latter to a transverse shaft 87 and journaled in the corresponding side frame 2 adjacent the rear end. Through another chain 88, the shaft 89 of a differential gear unit 90 mounted on base 1. By a system of bevel gears 91, the shaft 89 is connected to an axially-aligned shaft 92, which, through spur gears 93 is connected in turn to a parallel shaft 95 of the unit 90. Through the medium of additional speed-reducing sprocket chain gearing 96, 97, the shaft 95 is constantly driven from a pilot motor 98 supported on the base 1 adjacent the unit 90. Through interposed gearing 99, 100 and 101, the movements of the shaft 92 of the unit 90 are transmitted to a sprocket wheel 102 on the actuating shaft 103 of a rheostat 105 which is relied upon to regulate current flow to the motor 59. The sprocket wheel 102 is coupled to the shaft 103 of rheostat 105 by a spring clutch means 102a which will slip under certain conditions. The A. C.-D. C. motor generator set indicated at 106 in Fig. 2 furnishes the current for the pilot motor 98. The circuits for the various electric instrumentalities employed in the control system may be like that shown in the reference patent supra, except that, in the present instance, a switch 107 (Figs. 1, 3, 4) is interposed with its spring-biased actuating lever 108 in the path of one of the arms 60. As the arm 60 swings outward incident to doffing of the beam 21 as presently explained, the switch 107 automatically opens to break the control circuits and so prevents operation of the motor 59 at such time.

Compressed air or other fluid pressure medium for actuation of the cylinder 11 is conducted through a pipe line 110 from a suitable source of supply (not illustrated) to a combined regulator-

filter-lubricator unit conventionally shown at 111 in Fig. 1. A pipe 112 leads from the unit 111 to a manual controlled three way valve 113 which is in communication with opposite ends of cylinder 11 by way of pipes 115 and 116, and which exhausts through a pipe 117. Interposed in pipe 115 is a manually-operable adjustable restrictor valve 118, and connected into the rear end of the cylinder is an adjustable bleed valve 119 which may be of the needle type.

In practice, the apparatus is provided, of course, with combs or reeds for keeping the warps separated as they travel to the beam, but since such devices are well known in the art, illustration of them herein has not been considered necessary.

Operation

In preparation for the operation of the apparatus, the treadle 69 is depressed to withdraw the latches 68, whereupon the arms 60 are drawn forwardly past dead center by means of the grasp 66, with incidental taking up of the slack in the chains 70. The valve 113 is then operated for admission of air to the rear end of cylinder 11 to move the piston rod 10 of the latter forwardly with the cross bar 9 and the carriages 5. The arms 60 are thereby allowed to swing by gravity to the position in which they are shown in Fig. 4, for engagement of their notches 63 over the journals 32 of an empty beam 21 previously rolled into position to the front of the apparatus. The keeper elements 65 are next lifted to lock position for temporary retainment of the beam journals 32. With this accomplished, the valve 113 is reversed to admit compressed air into the front end of cylinder 11 for retraction of the piston rod 10 and the parts connected thereto. As such retraction takes place, the arms 60 are swung inwardly of the machine by the induced draw of the chains 70. As a consequence, the empty beam is lifted and its trunnions 32 passed into the arcuate slots 31 (which slots are curved concentrically with the axis of rock shaft 61) in the heads 27 until centered with respect to the latter, whereupon the valve 14 is returned to normal neutral position. The screws 38 are next rotated to move the jaw pieces 35 inwardly of the heads 27 to clamp the beam journals 32 as in Fig. 6. As the jaw pieces 35 recede in the heads 27, the pins 46 are urged inwardly by the springs 51 for projection of their rounded ends into the apertures in the beam flanges 48. Finally, the keeper elements 65 are depressed to release the arms 60 which are then swung back to the normal idle position of Figs. 1, 2, 3, with incidental slackening of the chains 70 and closing of the switch 107. The valve 113 is now moved to admit compressed air this time to the rear end of cylinder 11 for advancement of the pressure roll 8 into engagement with the body of the beam 21, said valve being kept in the position to which it was last moved throughout the beaming cycle which follows.

All being now in readiness, the motor 59 is started and the beam 21 driven in the direction of the arrow in Fig. 1. During the beaming, the roll 8 is maintained in constant but yielding pressure contact with the warp yarns as they build up on the beam 21 by the action of the cylinder 11, spasmodic movement thereof as it recedes with gradual increase in the diameter of the warp accumulation on the beam being prevented by the action of the snubbers 22. In receding, the press roll 8 is held in true parallel-

ism with the beam through cooperation of the rack bars 17 with the pinions 18 as will be readily understood; while through the chain connections 78 and 88, the differential unit 90 is automatically controlled to bring about gradual decrease in the speed of the motor 59 for maintenance of a uniform tension on the warps throughout the beaming cycle, in the same manner as set forth in the patent hereinbefore referred to. Moreover during the beaming cycle, the pressure in cylinder 11 is kept constant by the bleeding action of the valve 119. After the desired amount of yarn has been collected on the beam 21, the apparatus is stopped, and the valve 113 moved back to neutral to cut off further flow of compressed air to the cylinder 11.

In preparation for doffing the filled beam, the arms 60 are moved forward manually to engage the beam journals 32 within the notches 63, and the keeper elements 65 are lifted into lock position. The jaw pieces 35 in the heads 27 are next retracted, with attendant withdrawal of the pins 46, to release the beam journals 32, and compressed air is thereafter admitted into the front end of cylinder 11 to take up the slack in the chains 70, and the valve 113 then manipulated to exhaust the air from said cylinder and so gradually let down the beam until it rests on the floor. As a last step, the keeper elements 65 on arms 60 are depressed to free the trunnions 32 of the filled beam, whereupon the latter is rolled away in readiness for the substitution of a fresh empty beam in the apparatus in the same manner as before.

It is to be understood that we do not consider ourselves limited to the precise details of construction and arrangement herein shown and described by way of example, since these are obviously subject to considerable modification within the scope of the broader of the appended claims.

Having thus described our invention, we claim:

1. In a textile beamer or warper, a rotatively-supported driven-beam; an associated press-roll; a transversely-arranged carriage with bearings in which the press roll is journaled in the same horizontal plane with the axis of the beam; a fixed guide-way by which the carriage is constrained for rectilinear movement of the press roll relative to the beam; yielding means influential upon the carriage to maintain the press roll in contact with the winding on the beam; a crosswise shaft rotative in fixed bearings; and spur pinions affixed to said shaft and meshing with toothed racks respectively at opposite sides of the carriage for maintaining the press roll at all times in true parallelism with the beam.
2. A textile beamer or warper according to claim 1, wherein the yielding means is in the form of a stationarily-supported pressure fluid cylinder with its piston rod connected to the rear end of the carriage.
3. A textile beamer or warper according to claim 1, wherein the yielding means is in the form of a stationarily-supported double acting fluid pressure cylinder with its piston rod connected to the rear end of the carriage; and further including manual valve means whereby pressure fluid can be admitted to the front end of the cylinder concurrently with exhausting of the rear end for retraction of the press roll from the beam preparatory to doffing of the latter.
4. A textile beamer or warper according to claim 1, further including bars longitudinally of opposite sides of the carriage; and fixedly posi-

tioned slip friction clamp devices for restraining said bars to prevent spasmodic action of the press roll during the beaming.

5. In a textile beamer or warper, means including a motor with a speed control for driving the beam; an associated press roll; pressure fluid actuated means for maintaining the roll in yielding rolling contact with the warp winding on the beam during the beaming; and means actuated from the press roll for governing the speed control of the motor to reduce the speed of the beam compensatively with increase in the diameter of the warp accumulation thereon, for maintenance of a uniform tension upon the warps.

6. In a textile beamer or warper, a rotatively-supported beam; an associated press roll; a carriage with bearings in which the shaft of the press roll is journaled; a fixed horizontal guideway by which the carriage is constrained for rectilinear movement of the press roll relative to the beam; yielding means influential upon the carriage to maintain the press roll in contact with the winding on the beam; an electric motor and intermediate connections for driving the beam; and means for controlling the speed of the motor for maintenance of uniform tension on the warps during the winding including an associated rotary rheostat; a differential gear device for actuating the rheostat driven by an auxiliary constant speed motor and having a regulating shaft; a spur pinion on the shaft of the press roll; an intermeshing spur gear with its shaft rotatably supported on the carriage; a sprocket wheel on the last mentioned shaft; a chain connecting the sprocket wheel with sprocket wheels on shafts adjacent opposite ends of the guideway, and a sprocket chain connection between one of the latter shafts and the regulating shaft of the differential device.

7. In a textile beamer or warper, a pair of side frames; heads at the inner ends of unison-driven spindles rotatively supported in the side frames, said heads having means axially for reception of journal projections of a beam upon which the warps are to be wound; means for releasably connecting the beam to the heads for rotation thereby; a press roll; means for moving the press roll toward and away from the beam, and for maintaining it in rolling contact with the latter during the beaming, including a horizontally-arranged double-acting pressure fluid cylinder, and slide carriage means rotatively supporting the press roll and connected to the piston rod of the cylinder; and beam mounting and doffing means including a pair of vertically-arranged lift arms affixed at their lower ends to a positionally-fixed transverse rock shaft and having releasable means at their distal ends for engaging the journals of the press roll, and connections through

which said arms are actuated from the cylinder aforesaid to initially mount the beam in the warper, and to doff the beam at the completion of the beaming cycle.

8. A textile beamer or warper, according to claim 7, wherein the lift arms of the beam mounting and doffing means have laterally-open notches at their distal ends to engage over the journals of the beam, and retractable keeper means for retaining the beam trunnions in said notches during mounting and doffing.

9. A textile beamer or warper, according to claim 7, wherein arcuate slots, with their center of curvature in the axis of the rock shaft, extend from the peripheries of the heads to the centers of the latter for entry of the beam journals; and further including retractable means to prevent displacement of the beam journals from the bottoms of the slots in the heads during the beaming.

10. A textile beamer or warper, according to claim 7, wherein the drive axis of the beam is in a vertical plane somewhat outward of the vertical plane containing the rock shaft for the lift arms of the beam mounting and doffing means, so that when in operative position, said arms are inclined past dead center to permit gravitation of the beam during doffing under restraining control of the cylinder.

11. A textile beamer or warper, according to claim 7, wherein the drive axis of the beam is in a vertical plane somewhat outward of the vertical plane containing the rock shaft for the lift arms of the beam mounting and doffing means, so that when in operative position, said arms are inclined past dead center to permit gravitation of the beam during doffing under restraining control of the cylinder; and wherein the lift arms are connected to the press roll carriage means by chains.

12. An electric motor-driven textile beamer or warper, according to claim 7, wherein the lift arms of the beam mounting and doffing means normally occupy an idle position withdrawn from the beam journals during beaming; further including switch in circuit with the motor arranged to be opened upon movement of said arms to active position in preparation for doffing.
